UNITED STATES PATENT OFFICE.

PRIME EDWARD GANNON, OF JEROME, ARIZONA.

CONVERTER-VALVE.

1,034,995.

Specification of Letters Patent.

Patented Aug. 6, 1912.

Application filed March 13, 1912. Serial No. 683,485.

To all whom it may concern:

Be it known that I, PRIME EDWARD GANNON, a citizen of the United States, and a resident of Jerome, in the county of Yavapai and State of Arizona, have invented a new and useful Improvement in Converter-Valves, of which the following is a specification.

My present invention relates to valves of that character which are utilized in connection with the wind boxes of converters, particularly copper converters, and which are adapted to permit of the insertion of a rod therethrough, such rod being extended through the twyer for the purpose of preventing the latter from clogging while the impurities are being blown out of the copper.

Ordinarily, valves of the present character have been made in sections, that section which carries the valve member being secured to the inside of the wind box cover, thus necessitating the removal of such cover when replacing a defective valve. It will be at once seen that removing the wind box cover in turn necessitates shutting down the converter.

My present invention grows out of the deficiencies above noted, and its object is to provide a valve which may be secured to the wind box cover in such a manner that it may be replaced without interfering with the operation of the converter.

Other objects, and the advantages, of my invention will be apparent from the following description and the accompanying drawing, which forms a part of this specification, and in which,

Figure 1 is a vertical section through a converter showing the practical application of my improved valve; Fig. 2 is a central longitudinal section through my improved valve removed, and Fig. 3 is a transverse section therethrough taken on the line 3-3 of Fig. 2 and looking in the direction of the arrow.

Referring now to these figures, I have shown a converter A, in Fig. 1, as provided with a twyer a and a wind box a' secured thereto around the twyer and having its cover a² provided with an opening a³. My improved valve is cast in one piece and comprises a tubular body portion B, the bore B' of which is provided intermediate its ends with an enlargement as shown at B² in Fig. 2, thus forming a circular shoulder B³, the purpose of which will be hereinafter pointed

out. The enlarged portion B² of the bore constitutes one end of the bore C' formed within an angularly inclined enlargement C of the body B, and in which bore C' is arranged the valve member D, at present shown in the form of a ball or sphere. Inasmuch as the bores B' and C' intersect one another, the valve member D, being free to move in the latter, normally assumes the position shown in Fig. 2, and when the valve is properly positioned in connection with the wind box, as shown in Fig. 1, the valve member D is held seated against the shoulder B³. The enlargement C inclines outwardly toward one end of the body B and the latter is provided at its opposite end with an outstanding attaching flange E, having upon its inner face, embossed gasket rings E¹ and E² which are arranged concentrically and in spaced relation, and between which the flange E is provided with transverse openings E³, the latter being adapted for the reception of suitable members for the purpose of fastening the flange upon the outer surface of the wind box cover a² in the position as shown in Fig. 1.

In practical operation, a rod such as shown in dotted lines at F in Figs. 1 and 2, is introduced through the bore B' of the body B and tends to raise the valve member D upwardly in the bore C' of the enlargement C, in order that the rod may pass inwardly through the valve and through the twyer a whereby to prevent the latter from clogging while the impurities are being blown out of the copper within the converter.

From the foregoing, it will be apparent that it is essential that my valve be cast in one piece in order that when attached to the wind box cover A², as shown in Fig. 1, it may be removed as a whole and quickly replaced without interfering to a serious extent with the operation of the converter. In order that the valve member D may be properly positioned as described, I preferably embed the same in the core, which, in the operation of molding the valve, forms the bore B' in the body and the bore C' in the body enlargement. Thus when the core is subsequently removed, the valve member D remains inclosed.

In the formation of the valve, any materials which will resist a heat of 300 degrees F. will suffice, and while it is probable with some of these materials, such for instance as

steel, it will be necessary to insert a machined seat for the valve member D, within the valve in substantially the same manner as the said valve member is inserted, with 5 most of the materials such as cast iron, brass and aluminum it is simply necessary to stand the valve upright; on its flanged end and by inserting a tool within the opposite end of the bore B' and striking the valve member 10 several sharp blows, it will form its own seat. Likewise, when the valve flange E is secured to the wind box cover a^2 , the flange is lightly tapped and this tapping together with the tightening of the fastening members causes the gasket rings E' and E² to 15 slightly flatten and compress against the outer surface of the cover.

I claim:

In a valve of the character described, a 20 casing cast in one piece and comprising a tubular body portion having an outstand-

ing attaching flange at one end and an angular enlargement adjacent its opposite end, said enlargement being inclined away from 25 said flange and having a bore intersecting that of the body, said bore of said enlargement being of greater cross section than that of the body whereby to form a circular shoulder extending around the body bore at the point of intersection of the bores, which 30 shoulder constitutes a valve-seat, a ball slideable in said enlargement and constituting a valve, said ball being of greater cross section than the bore of the body whereby to adapt the same to seat against the said 35 shoulder and to prevent its removal from the said enlargement.

PRIME EDWARD GANNON.
